BOTTOM-CASTING HOLLOW INGOTS

George Robson, Johannesburg, South Africa, assignor to The Union Steel Corporation (of South Africa) Limited, Johannesburg, Union of South Africa, a South African company

Application October 8, 1934, Serial No. 747,451
In South Africa November 8, 1933

13 Claims. (Cl. 22—141)

This invention relates to the bottom-casting of hollow ingots, in which the ingot is cast in a mould around a core and/or tubular liner, and has particular reference to the casting of such ingots for use in manufacturing hollow drill steel.

It has been found in practice that there is a tendency for the molten metal entering the mould to cause "scouring" of the walls of the latter at its lower end, with the result that the cast ingot in solidifying in the mould binds therein and is fractured by contraction strains and in consequence a considerable portion of the resulting rolled bar has to be cut off and discarded as waste.

Also, where a central metal tube containing a metallic core is employed, there is a tendency for the tube to be wholly or partially fused and washed away by the impingement of the molten metal against its surface, and beads of the molten steel can thus find their way into the space between tube and core, thus binding the core in the resulting hollow ingot and making it difficult subsequently to withdraw the core from the rolled bar of hollow drill or other steel.

For the purpose of avoiding damage of the mould walls or core by the molten metal, it has already been proposed to give the mould interior such a cross-section that the distance between the walls of the mould and the core are different at different places and to arrange the inlet opening or openings for the molten metal at the places in the bottom of the mould where such distances are greatest, as for example, by making the mould chamber of square section and locating the inlet opening or openings on a diagonal line in the bottom of the said chamber. With this arrangement, however, the ingots produced are defective because of their irregular shape inevitably results in uneven dendritic growth, which cannot be fully corrected in subsequent rolling, and in consequence of piping troubles, the yield of finished bar from the ingot is generally not greater than about 75%.

A further drawback which is present in bottom-casting processes proposed heretofore is that considerable time and labour are occupied in locating the mould accurately by hand relatively to the sand runner-brick upon which the core and/or tubular liner is or are placed.

The object of the present invention is to overcome the aforementioned defects, to reduce the time and labor occupied as aforesaid, and enable a greater yield and better structure of finished metal to be obtained.

According to one feature of the invention, I provide a method of bottom-casting hollow ingots, wherein the casting is carried out in a mould in which the minimum path for the molten metal between the inlet or inlets of the runner-brick and the mould wall, and between such inlet or inlets and the tubular liner and/or core, lie in different planes so that the metal reaches the said wall and liner and/or core as late as possible after entering the mould consistently with the size thereof. 5

According to a further feature of the invention, I provide a method of bottom-casting hollow ingots in which the mould is self-centering or otherwise self-positioning with respect to the core 15 and/or tubular liner (hereinafter simply referred to generally as the "core"), thereby ensuring accuracy in the radial dimensions of the ingot, and avoidance of damage to the mould wall and core. More specifically, I carry out the casting 20 in a mould of substantially circular shape so as to ensure regular dendritic growth, and the molten metal is introduced through an inlet or inlets located in or about the angle between a surface or surfaces extending laterally of the 25 core and a surface or surfaces extending longitudinally thereof, so that said surfaces intervene between the hot metal initially introduced and the mould walls and core.

In accordance with a further feature of the 30 invention, the casting is carried out in a mould having, at the bottom thereof, a runner-brick with an upstanding projection or projections whereby the length of ingot cast in the mould is determined, the metal connecting the body of 35 the ingot with the runner or feeder of the brick, after solidification, constituting a weak spot at which, if the ingot tends to bind in the mould, any resulting fracture can take place.

My invention also comprises the provision of 40 means for bottom-casting hollow ingots comprising a runner-brick having one or more upstanding projections adjacent to the core and an inlet or inlets for the molten metal located close to the said projections, as far as possible below the 45 core and inwardly of the mould wall as the size of ingot to be cast permits. The runner-brick may have the projection or projections thereon so shaped and arranged as to facilitate or ensure 50 centering or like positioning of a two-part or like mould relatively to the core, thereby saving time and labour in assembly. More specifically, the runner-brick may be provided on its upper surface with a plug-like projection rounded to fit 55

within the end of a circular mould, and provided with a central socket for the reception of the core.

In a preferred embodiment, the runner-brick is provided with an upstanding plug having its side faces rounded at opposite sides to fit within a circular mould and formed with recesses or openings adapted to provide, in conjunction with the wall of the mould, passages or ducts above the holes in the brick through which the molten metal enters the mould, said passages or ducts being of substantially greater cross-sectional area than said holes and serving to reduce the velocity and temperature of the entering metal before reaching the core.

15 The invention will now be described by way of example, with reference to the annexed drawings, in which—

Figure 1 is a view of the runner-brick in longitudinal section;

20 Figure 2 is a plan view of the brick;

Figure 3 is a perspective view;

Figure 4 is a diagrammatic view showing plug-like runner-brick projections of different height;

25 Figure 5 is an outside elevation of the brick on a reduced scale with a mould laid thereon, the mould being shown diagrammatically.

Figure 6 is a part sectional view of an apparatus embodying the present invention.

Referring to the drawings:—

30 The upper surface 1 of the runner-brick is formed with a plug-like projection 2 having rounded side faces 3, 4 of a diameter corresponding to the inner diameter of the mould with which the brick is to be used. Arcuate recesses 5, 6 are provided above holes 7, 8 communicating with a feeder passage 9 running longitudinally through the brick. The recesses 5, 6 are adapted to provide in conjunction with the wall α of the mould (shown diagrammatically in Figure 4) passages 35 or ducts of larger cross-sectional area than the holes 7, 8. The plug-like projection 2 is formed of refractory material in one piece with the remainder of the brick, and at the top of the projection 2 a recess 10 is provided for the accommodation of the lower end of a core and lining tube such as illustrated diagrammatically at 11 in Figure 5.

35 The holes 7, 8 are located as close as possible to the adjacent recessed sides of the plug-like projection 2, thereby providing a maximum distance between each said hole and the corresponding adjacent part of the mould wall adapted to rest on the brick, while simultaneously preserving a sufficient distance between each said hole and the top of the projection 2 on which the core and tube rest.

40 By this means the separations possible in any given size of mould between the entering molten steel, mould wall and central tube are lengthened and scouring of the mould and fusion and collapse of tubes are eliminated or reduced. In practice I have found that with the use of the runner-brick described it is possible to treble the life of the moulds and no trouble is experienced through 45 fast cores.

The runner-brick also enables a round mould to be successfully employed and due to uniform and rapid cooling, regular radial dendritic growth is ensured. I have found from experience that 50 by the use of the runner-brick described, in conjunction with a mould as set forth in my co-pending patent application Serial No. 747,452, filed October 8, 1934, it is possible to secure a yield of finished metal of 67½ per cent. The combination of the said mould and brick also gives

an ingot which is not liable to bind in the mould and pull at any point in the body, since if there is any tendency to binding this takes place at the weak point at the bottom where the two thin legs of steel straddle the plug-like projection 2 and 5 connect up with the feeder passage 9, where, after a little use, the mould will in any case be slightly larger in diameter. Moreover, the fact that the plug-like projection 2 ensures self-centering of the mould and core not only reduces 10 time and labour of assembly, but makes possible the use of an improved type of mould with solid top portions, as described in our aforesaid co-pending patent application.

15 As illustrated diagrammatically in Figure 4, 15 bricks having plug-like projections 1a, 1b, 1c of different height may be employed in conjunction with the same mould so that the length of ingot cast therein may be varied, and thus desired finished lengths of bars of the same or different section obtained while using the same mould. For example, as shown in Fig. 6, bricks having high 20 projections may be placed under the moulds nearest the trumpet 12 through which the hot steel or metal is fed, while bricks with lower projections 25 may be inserted under the moulds further away from the trumpet. The higher projections protect the nearest ring of ingots from the risk of collapsed tubes and fast cores. Similarly, by setting up one plate of moulds with bricks having 30 tall projections and another plate with bricks having lower projections, it is possible to cast two plates from the same ladle of steel successfully.

35 I claim:—

1. Means for bottom-casting hollow ingots, comprising a runner-brick having holes in the upper surface thereof for passage of molten metal, a mold supported on the runner-brick, and an upstanding projection provided upon the runner-brick, said projection having its side faces 40 so shaped as to fit within the mold to facilitate centering of the mold on the runner-brick and so as to form with the wall of the mold ducts above the holes in the runner-brick through which the molten metal enters the mold.

2. Means for bottom-casting hollow ingots, comprising a runner-brick having holes in the upper surface thereof for passage of molten metal, a mold supported on the runner-brick, and an upstanding projection provided upon the runner-brick, said projection having its side faces so shaped as to fit within the mold to facilitate centering of the mold on the runner-brick and so as to form with the wall of the mold ducts 5: above the holes in the runner-brick through which the molten metal enters the mold, the ducts being of greater cross-sectional area than the holes.

3. Means for bottom-casting hollow ingots, comprising a runner-brick having holes in the upper surface thereof for passage of molten metal, a mold supported on the runner-brick, and an upstanding projection provided upon the runner-brick, said projection having its side faces 6: so shaped as to fit within the mold to facilitate centering of the mold on the runner-brick and so as to form with the wall of the mold ducts above the holes in the runner-brick through which the molten metal enters the mold, and said projection being formed of the same material as the body of the runner-brick.

4. Means for bottom-casting hollow ingots, comprising a runner-brick having holes in the upper surface thereof for passage of molten 7

metal, a mold supported on the runner-brick, and an upstanding projection provided upon the runner-brick, the projection having its side faces so shaped as to fit within the mold to facilitate 5 centering of the mold on the runner-brick and so as to form with the wall of the mold ducts above the holes in the runner-brick through which the molten metal enters the mold, the ducts being of greater cross-sectional area than 10 the holes, and said projection being formed of the same material as the body of the runner-brick.

5. Means for bottom-casting hollow ingots, comprising a runner-brick having holes in the 15 upper surface thereof for passage of molten metal, a mold supported on the runner-brick, and an upstanding projection having its side faces so shaped as to fit within the mold to facilitate centering of the mold on the runner-brick and so as to form with the wall of the mold ducts 20 above the holes in the runner-brick through which the molten metal enters the mold, and said projection being formed of the same material as the body of the runner-brick and integrally there- 25 with.

6. Means for bottom-casting hollow ingots, comprising a runner-brick having holes in the upper surface thereof for passage of molten metal, a mold supported on the runner-brick, 30 and an upstanding projection provided upon the runner-brick, the projection having its side faces so shaped as to fit within the mold to facilitate centering of the mold on the runner-brick and so as to form with the wall of the mold ducts 35 above the holes in the runner-brick through which the molten metal enters the mold, the ducts being of greater cross-sectional area than the holes, and said projection being formed of the same material as the body of the runner-brick, 40 and integrally therewith.

7. Means for bottom-casting hollow ingots, comprising a runner-brick having holes in the upper surface thereof for passage of molten metal, a mold supported on the runner-brick, 45 and an upstanding projection provided upon the runner-brick, the projection having its side faces so shaped as to fit within the mold to facilitate centering of the mold on the runner-brick and so as to form with the wall of the mold ducts 50 above the holes in the runner-brick through which the molten metal enters the mold, and the projection being provided with a central recess for the reception of the ingot core and being adapted to support the core above the level of the holes 55 in the brick.

8. An apparatus of the character described, comprising a pouring trumpet, a plurality of runner-bricks having ducts extending longitudinally therethrough, said runner-bricks being successively spaced from said trumpet and having their 60 ducts serially connected to said trumpet, each of said runner-bricks having openings extending through the upper surface thereof, and a mold-centering projection on the upper surface of each 65 brick, the projections on the bricks nearest the

trumpet being higher than the projections on the bricks farther away from the trumpet.

9. An apparatus of the character described, comprising a pouring trumpet, a plurality of runner-bricks having ducts extending longitudinally therethrough, said runner-bricks being successively spaced from said trumpet and having their 5 ducts serially connected to said trumpet, each of said runner-bricks having openings extending through the upper surface thereof, mold-centering projections on the upper surface of said runner-bricks having cut-away portions to provide paths for the flow of molten metal from said 10 openings, and molds mounted on said runner-bricks surrounding said projections, the projections on the bricks nearest the trumpet being higher than the projections on the bricks farther 15 away from the trumpet.

10. Means for bottom-casting hollow ingots comprising a runner-brick provided with an up- 20 standing projection having its side faces rounded at opposite sides to fit within a circular mould and formed with openings adapted to provide, in conjunction with the wall of the mould, ducts 25 above the holes in the brick through which the molten metal enters the mould, said ducts being of substantially greater cross-sectional area than 30 said holes.

11. Means for bottom-casting hollow ingots comprising a runner-brick provided with an up- 35 standing projection having its side faces rounded at opposite sides to fit within a circular mould and formed with openings adapted to provide, in conjunction with the wall of the mould, ducts 40 above the holes in the brick through which the molten metal enters the mould, said ducts being of substantially greater cross-sectional area than 45 said holes and said projection being formed of the same material as the body of the runner-brick.

12. Means for bottom-casting hollow ingots comprising a runner-brick provided with an up- 50 standing projection having its side faces rounded at opposite sides to fit within a circular mould and formed with openings adapted to provide, in conjunction with the wall of the mould, ducts 55 above the holes in the brick through which the molten metal enters the mould, said ducts being of substantially greater cross-sectional area than 60 said holes, the projection being formed integrally with the body of the runner-brick.

13. Means for bottom-casting hollow ingots comprising a runner-brick provided with an up- 65 standing projection having its side faces rounded at opposite sides to fit within a circular mould and formed with openings adapted to provide, in conjunction with the wall of the mould, ducts 70 above the holes in the brick through which the molten metal enters the mould, said ducts being of substantially greater cross-sectional area than 75 said holes and said projection being formed of the same material as the body of the runner-brick and integrally therewith.
